CENTRIFUGAL APPARATUS

Filed Aug. 10, 1926

FIG. 2

Champlain L. Riley
INVENTOR.

UNITED STATES PATENT OFFICE

CHAMPLAIN L. RILEY, OF NORTH PLAINFIELD, NEW JERSEY, ASSIGNOR TO INDUSTRIAL ASSOCIATES, INCORPORATED, OF NEW YORK, N. Y., A CORPORATION OF NEW YORK

CENTRIFUGAL APPARATUS

Application filed August 10, 1926. Serial No. 128,445.

My invention relates to centrifugal apparatus, and particularly to the mounting and drive of a centrifugal unit, such as a nebulizer. The object of my invention is to provide a simple and efficient mechanism adapted for very high speed rotation, say from 5,000 to 12,000 revolutions per minute.

In the accompanying drawings,

Fig. 1 is a vertical section through a centrifugal apparatus of the nebulizer type, in which my invention is embodied in one form; and

Fig. 2 is a section on the line 2—2, Fig. 1.

While the features to which my invention relate, may be embodied in apparatus of various types, I have illustrated them by way of example in a layout adapted to the high speed rotation of the nebulizer 15, of the general construction shown in my Patent 1,624,847 and in my copending applications Ser. Nos. 97,136, filed March 24, 1926; and 98,838, filed March 31, 1926. Nebulizers of this type are particularly well adapted for use in the spray drying of fluids, muds, etc., and I have accordingly indicated the apparatus installed at an opening 16 in the top wall 17 of a spray chamber 18 through which a current of air, generally preheated, is drafted in well understood fashion.

A standard 19 of any suitable character is supported on the top wall 17 of the chamber, and carries the vertical driving spindle 20, which rotates in stationary bearings 21 and 22. It also supports, through the rock bearing 23, the suspended shaft 24, to the lower end of which the nebulizer unit 15 is attached. A flexible coupling 25, of any suitable character, between the driving spindle 20 and the suspended shaft 24, serves to transmit to the latter the rotation of the former. The nebulizer has a ball-joint connection with the lower end of the driving shaft, so that its plane of rotation may assume various angular positions with respect to the axis of the shaft 24 during operation. To this end the web 26 of the unit is provided with a spherical hub 27 clamped between the bearing washers 28 and 29 by the nuts 30 on the pin 31, which passes with clearance through the central hole 32 through the ball hub 27 and takes

into the lower end of the shaft 24. While the frictional engagement of the hub 27 with the washers 28 and 29 is sufficient to insure the drive of the nebulizer unit 15, the latter is nevertheless free to assume an angular position with respect to the axis of the shaft 24 under the stresses set up during operation of the apparatus.

The layout thus provides (1) a driving spindle rotated in fixed bearings, (2) a suspended shaft flexibly coupled thereto and having a suspension bearing which permits the shaft to gyrate; (3) a nebulizer unit supported at the lower end of the suspended shaft by means of a flexible joint which permits the nebulizer to automatically assume such angular position with respect to the axis of the shaft as working conditions necessitate for stability.

It will be noted that in the layout shown the aperture 16 in the top wall of the driving chamber is substantially closed by a diaphragm 33, having a relatively small central opening 34 through which the suspended shaft passes. This arrangement is preferred since it serves to more or less isolate the driving spindle and its connections from the heat of the drying chamber 18. The lubricating system to which reference is hereinafter made, as well as the bearings, are thus kept cool—more particularly as the draft through the drying chamber is usually effected by suction, and any air entering the standard 19 is drafted therethrough and through the opening 44 into the drying chamber. This is important also from the standpoint of maintenance of these parts free from deposit of solids thereon as a result of the drying operation in the chamber 18.

The margins of the opening 34 serve as a positive limit to the gyration of the shaft 24.

A gyration brake is afforded by a group of brushes 35 bearing against the periphery of the shaft 24 at a point remote from its suspension. These brushes 35 are here shown mounted on the lower face of the bottom 36 of a hood 37 which extends downward into the drying chamber from the diaphragm 33. The brushes project beyond the margins of the hole 38 in the bottom 36 of the hood 100

- through which the shaft 24 passes. They are outwardly displaceable through their supporting straps 39 secured to the hood bottom 36, but are stressed inward by springs 40. 5 The latter may conveniently be pull springs, the opposite ends of which are connected to the ends of stirrups 41 which bear against the outer ends of adjacent brushes 35.
- The brake brushes 35 are preferably located 10 at substantially the center of oscillation or percussion of the shaft 24, and its supported load. In order that this point may be spaced at some distance from the point of support of the shaft, the latter is preferably made 15 hollow or cylindrical throughout the greater portion of its length, as indicated at 42, thus locating the center of gravity of the shaft and the suspended nebulizer unit 15 well below the longitudinal center point of the suspended 20 shaft. As is well understood, the center of gravity is an element which enters into the determination of the center of oscillation or percussion. By locating the brake brushes at this latter point, their restraining effort on 25 the shaft is not only maximum, but is without tendency to cause vibration of the shaft. In high-speed apparatus of the present character, vibration is an element of danger, and its elimination is of first importance.
- 30 It will be noted that the hood 37 is closed and thus also serves to prevent the deposit of solids from the drying chamber upon the rotating parts, with possible resultant establishment of unbalanced conditions. To protect the brushes 35 from deposits, I prefer to enclose them within the shield 43 secured to the bottom 36 of the hood, and having a central opening 44 of sufficient size to permit limited gyration of the shaft 24.
- 40 The fluid supplied to the nebulizer unit 15 may be derived from any suitable source, such as a container, diagrammatically shown at 45, from which it is led by pipe 46 through hood 37 to the feed nozzle 47.
- 45 The drive and lubrication of spindle 20 and its associated parts is effected in any suitable fashion. I have indicated, by way of example, a driving pulley 48 at the head of the spindle, and preferably having a ratchet drive connection therewith to insure the rotation of the spindle in predetermined direction. The drive of the spindle, however, may be accomplished by any suitable means, for example, a turbine, electric motor, or the like, 50 where this is feasible. When a pulley drive is utilized it forms the head by which the spindle 20 is suspended in its bearings. The pulley hub 49 rests through bearing washers 55 upon the bearing bush 21. The suspended 55 shaft 24 is supported at the lower end of the bearing body 51 by a screw bushing 52 within which the ball rocker 23 is accommodated.
- Lubricant may be supplied from the cup 53 through channel 54 to the chamber 55 within 60 which the washers 50 are located. An oil 65

chamber 56 between the bearing bushings 21 and 22 receives excess lubricant, as does also the chamber 57 which surrounds the flexible coupling 25. The spindle 20 may be spirally grooved as at 58 to circulate lubricant from 70 chambers 57 and 56 to the chamber 55, while pipe 59 establishes communication between the chambers 55 and 56 to take the overflow from chamber 55. From chamber 57 the lubricant passes through the suspension bearing 23 to spout 60, which in turn delivers to a receptacle 61, where it is recuperated for 75 cleaning and re-use.

It will be noted that all the lubricated parts 80 are above the diaphragm 33 and are thus well protected from the heat of the drying chamber 18. The brushes 35 which are subject to the heat of the spray chamber, are of a character not affected by its temperature, such, e. g. as carbon or graphite.

It will be understood that the embodiment 85 of my invention above described and illustrated in the accompanying drawing is only illustrative of the thoughts which underlie my invention, which may be embodied in 90 other structures without departing therefrom.

I claim—

1. Centrifugal apparatus comprising a vertical spindle rotating in fixed bearings, a 95 shaft suspended below said spindle and flexibly coupled thereto, and a centrifugal unit flexibly mounted at the lower end of said suspended shaft, together with a gyration brake engaging said suspended shaft substantially 100 at the center of oscillation of said shaft and its supported load.

2. Centrifugal apparatus comprising a suspended, gyrating, driven shaft, a centrifugal unit suspended at its lower end, and a gyration brake engaging said shaft substantially 105 at the center of oscillation of said shaft and its supported load.

3. Centrifugal apparatus comprising a suspended, gyrating, driven shaft, a centrifugal 110 unit suspended at its lower end, and a spring stressed gyration brake engaging said shaft substantially at the center of oscillation of said shaft and its supported load.

4. Centrifugal apparatus, comprising a 115 suspended, gyrating, driven shaft, and a centrifugal unit flexibly connected to the lower end of the shaft to permit said unit to rotate in planes at various angles to the axis of rotation of the shaft, together with means 120 engaging the shaft at the center of oscillation of said shaft and its load, to damp its gyrations.

5. Apparatus of the type described comprising a drying chamber through which a 125 gaseous current is drafted, a top wall of the chamber having an opening therein, driving means mounted at said opening, a centrifugal nebulizer suspended within the chamber from said driving means, and housing means 130

protecting said driving means from deposit of solids thereon from the drying chamber said housing having an opening to the atmosphere through which a protective and cooling gaseous current may flow through the housing into the chamber incident to the suction effort exerted in the chamber.

6. Centrifugal apparatus comprising a suspended gyrating, driven shaft, and a gyration brake engaging said shaft substantially at the center of oscillation of said shaft and its supported load.

In testimony whereof I have signed my name to this specification.
